UNITED STATES PATENT OFFICE.

WILLIAM DEW KNIGHT, OF SANTA MONICA, CALIFORNIA.

HOT-WATER-CIRCULATING SYSTEM.

1,153,233.

Specification of Letters Patent. Patented Sept. 14, 1915.

Application filed August 8, 1913. Serial No. 783,781.

To all whom it may concern:

Be it known that I, WILLIAM DEW KNIGHT, a citizen of the United States, residing at Santa Monica, in the county of 5 Los Angeles and State of California, have invented certain new and useful Improvements in Hot-Water-Circulating Systems, of which the following is a specification.

This invention relates to water heating 10 devices or boilers and more particularly to a hot water circulating system to be herein-after fully described.

The primary object of the invention contemplates the provision of a simple and inexpensive boiler wherein a supply of cold 15 water is circulated or drawn through a suitable compartment provided therefor within the boiler; then heated exteriorly of the boiler by any suitable range or other heat 20 source, and finally conveyed back again into a second or the main compartment of the boiler in a heated state where it is free to be withdrawn when desired, this arrangement effecting a continuous water circulating system 25 for replenishing the hot water supply as occasion demands.

A further object of the invention resides in the provision of a specially constructed boiler, simple in design and capable of being 30 employed in connection with any suitable range, stove or other heat source susceptible of having a boiler connected thereto.

The above and additional objects are accomplished by such means as are illustrated 35 in their preferred embodiment in the accompanying drawings, described in the following specification and then more particularly pointed out in the claim which is appended hereto and forms a part of this application.

With reference to the drawings, wherein I have illustrated the preferred embodiment 45 of my invention, as it is reduced to practice, similar reference numerals designate corresponding parts; the view in the drawing being a vertical sectional view of the boiler, parts being shown in elevation, and the boiler compartments being only partly filled so as to better illustrate the interior structure thereof.

Referring now to the description of the drawings, the numeral 1 designates the boiler in its entirety having a cylindrical shell 2 extending concentrically throughout 55 the entire length thereof, the said shell being

provided with outwardly directed flanges 3 at each end for securely fastening the same in proper place within the boiler. A cold water inlet pipe 4 discharges into a suitable compartment 5 formed by the shell 2 from 60 the top of the boiler, the said inlet pipe 4 having an extension 6 arranged within the compartment 5 for conveying the water into the said compartment and preventing the rise of water therein above the mouth of the 65 said extension. A cold water outlet pipe 7 is secured to the boiler 1 at the opposite end thereof from that of the inlet pipe 4 or in axial alignment with the extension 6, the said outlet pipe 7 leading into a suitable tank or 70 other receptacle arranged within a range, stove or like heat source, the latter being omitted from the drawing. From the heat source, a hot water inlet pipe 8 conveys the water in its heated state again into the 75 boiler 1, the said pipe 8 discharging into a hot water compartment 9 formed within the boiler and surrounding the cold water compartment 5 thereof, this arrangement supplying the boiler with an unlimited supply 80 of hot water as the same is replenished through the inlet pipe 8 as quickly as it may be withdrawn from a suitable hot water outlet pipe 10, the latter having an extension 11 extending into the interior of the 85 boiler to a point near the base thereof.

To allow the steam generated by the hot water to escape from the compartment 9, an opening 12 is formed within the shell 2 near the top thereof, thus permitting the steam 90 to enter the cold water compartment 5 where it is condensed by the inflowing cold water, such condensation allowing the hot water, when not in circulation, to be maintained at a boiling temperature.

A drain pipe or valve 13 is open to the boiler at the base thereof for withdrawing the contents of the compartment 9 when desired. Pipe 7 is open to a branch pipe 14 (a valve being arranged at the point of intersection) whereby to provide for a discontinuation of the water supply to the heat source, if desired.

It will be seen from the above, taken in connection with the accompanying drawings, that the temperature of the cold water as it passes through the compartment 5 is increased by reason of the heated state of the compartment wall or shell 2; and that an unlimited supply of hot water may be 110

had, as hot water is supplied to the hot water compartment 9 as fast as it is withdrawn therefrom through the outlet pipe 10.

It will be understood that the above description and accompanying drawings comprehend only the general and preferred embodiment of my invention and that various minor changes in details of construction, proportion and arrangement of parts may be made within the scope of the appended claim and without sacrificing any of the advantages of my invention.

Having thus fully described my invention, what I claim as new and desire to secure by Letters Patent is:—

In a hot water circulating system, a boiler, a shell extending longitudinally throughout the length of the boiler for dividing it into a cold water compartment and 20 a hot water compartment, the said shell hav-

ing an opening formed therein at a point adjacent the boiler top, a cold water inlet pipe extending into said cold water compartment to a point below said opening, a cold water outlet pipe leading from said cold water compartment, a hot water return pipe discharging into the hot water compartment of the boiler at a point intermediate the boiler terminals, and a hot water outlet pipe leading from the boiler and extending thereinto to a point below the point open to the hot water return pipe, as and for the purpose set forth.

In testimony whereof I affix my signature in presence of two witnesses.

WILLIAM DEW KNIGHT.
